Primary Examiner—Freda S Nunn(74) *Attorney, Agent, or Firm*—Brinks Hofer Gilson & Lione(57) **CLAIM**

We claim the ornamental design for a display device, as shown and described.

DESCRIPTION

FIG. 1 is a front perspective view of a display device of the present invention;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a rear perspective view thereof shown in an environmental use; and,

FIG. 10 is a rear perspective view thereof shown in an additional environmental use.

The broken line showing of display device is included for the purpose of illustrating environment and forms no part of the claimed design.
